INVENTOR.

ARGYLE CAMPBELL
BY George J. Haight
HIS ATTORNEY.

UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

DUMP-DOOR-OPERATING MECHANISM.

Application filed February 7, 1925. Serial No. 7,464.

This invention relates to improvements in dump door operating mechanisms.

The invention more particularly relates to the means for locking and operating car door winding shafts and is particularly adapted to the type of car having a series of doors hinged longitudinally of the car and adapted to be operated from a position adjacent the side of the car.

10 Among the objects which my invention attains is that of improving the method of mounting locking and operating means with respect to a ratchet wheel on the operating shaft, whereby two pawls may be 15 conveniently disposed in the same plane and a single ratchet wheel utilized for rotating the operating shaft and also for locking it in position.

It is also a further object of my invention 20 to dispose the said operating and allied parts in such a manner as to obviate the necessity of having the parts projecting beyond the plane of the car ends when such operating mechanism is used on dump cars 25 having dump doors extending from end to end of the car body and thus assure the safety and convenience of train men in the discharge of their duties.

Further my invention resides in certain 30 other features and details such as will hereinafter be more fully pointed out and claimed.

In the drawings, Fig. 1 is a vertical side elevational view illustrating the end of a dump car of a type to which my improvements are particularly adaptable. Fig. 2 is a vertical end elevational view of slightly less than half of the end of the car illustrated in Fig. 1. Fig. 3 is a vertical sectional view of a portion of the car illustrated in Fig. 1 and taken on a line corresponding substantially to line 3—3 of Fig. 1. Fig. 4 is an enlarged view of the portion of the car illustrated in Fig. 1 illustrating 45 the corner of the car with my improved construction associated therewith and Fig. 5 is an end elevational view of a portion of the end of the car, illustrating the construction shown in Fig. 4, as seen when viewing the end of the car.

In the drawings 10 represents the vertical side wall of the car having an inwardly bent lower portion 11, side stakes 12, vertical end walls 13, body bolster 14, end sill 15, center sill 16 and dump doors 17—17.

An operating shaft 18 extends along the side of the car body beneath the inwardly inclined floor 11, and operates in suitable journals provided therefor. The doors 17—17 are each operatively connected to the shaft 18 by self-locking linkage mechanisms 19—19, which may be of any suitable kind.

Adjacent the end of the car body are angle irons 20 and 21 which are secured to 65 and depend from the vertical side wall 10, said angles being spaced apart a suitable distance to form vertical stiles to which grab irons 22, and sill step 23, are secured. Said angles are further connected by a cross 70 strap 24, to which is attached a foot guard 25, for the purpose of eliminating danger to train men incidental to the opening of the dump doors. As will be noted, the angle iron 21 is removed from the end of the car 75 a distance designated by the reference character 26, and is connected to the inwardly deflected portion 11 of the car side by a transversely extending plate 27, which is riveted to the angle 21, as shown at 28, 80 and is provided with a flange 29 adjacent the portion 11, which is riveted thereto as indicated at 30. The plate 27 is perforated, and the shaft 18 extends therethrough and terminates an appreciable distance from the 85 end wall of the car. The shaft 18 is adapted to be supported at the end of the car by a bearing bracket 31 riveted to the angle iron 21, as at 32, and to the transversely extending plate 27 as at 133. 90

Adjacent to the plate 27, there is fixedly mounted on the shaft 18 a ratchet wheel 33, having hubs extending on the opposite sides thereof as indicated at 34 and 35 respectively. The hub 34 is extended longitudinally 95 of the shaft and within the bearing 31, and is riveted to the shaft at 36, recesses 37 being formed in the periphery of the hub to accommodate heads of said rivet.

Rotation of the shaft is effected by means 100 of oscillatable mechanism designated generally by the reference character A. The mechanism A includes walls 38 and 39 respectively disposed on opposite sides of the ratchet wheel 33. The wall 38 is disposed 105 between the plate 27 and the ratchet wheel 33, and pivotally mounted on the hub 34 of the ratchet wheel 33. Preferably formed integrally with the wall 38, are bosses 40—40 which act as spacers between the respec- 110

tive oscillatable walls 38 and 39. Pivots mounted upon one of said bosses is an operating pawl 41 said pawl being arranged to engage the ratchet wheel 33 for rotating the same in either direction. The respective walls 38 and 39 are united by means of rivets 42 which preferably extend therethrough and through the bosses 40—40. The outer wall 39 which is mounted adjacent the end 10 of the shaft on the hub 35, is formed with a drumlike portion 43 which extends outwardly longitudinally of the shaft, and outwardly from the ratchet wheel 33, thereby providing additional bearing area on the hub 35, and beyond said portion 43, there is formed integrally therewith, a hollow socket portion 44, adapted to receive an operating bar, whereby rotation of the shaft is effected. The socket portion 44 is disposed to one side of the ratchet wheel 33, and the operating pawl 41, thereby providing for an unobstructed sweep of the latter as indicated by the circle 45 in Fig. 5, and a preferred location for the socket portion 20 is centrally of the center of rotation of the shaft adjacent the end of the same, and within the plane of the car end wall.

The means employed for securing the shaft against rotation during the operation 30 of the mechanism and also for locking the same in finally closed position, is indicated generally by the reference character B, and includes a locking pawl 46, and a locking cam 47, pivotally mounted between the transverse plate 27 and a spaced bracket 48. The bracket 48 is preferably of angle shape, one flange 49 thereof being secured to the inwardly directed sloping floor 11, and the other flange 50 being vertically disposed 35 and extending outwardly from said flange 49. The flange 50 is provided with a depression or pocket 51 in its upper side for a purpose hereinafter described.

The pawl 46, and cam 47, are respectively 45 mounted on pivots 53 and 52 which extend through the transverse plate 27 and vertical flange 50 of the bracket 48. The locking pawl 46 is adapted to engage the upper surface of the wheel, and said pawl under the influence of gravity is normally urged into locking engagement with the ratchet wheel 33. In order to hold the pawl out of engagement with the ratchet wheel, when it is 50 desired to release the mechanism, there is provided a lip 54 at the outer end of the pawl, under which the curved portion 55 of the cam 47 is adapted to engage. During the raising operation of the doors, however, there is a ratcheting action between the teeth 55 of the ratchet wheel 33 and the pawl 46 rendering it necessary that the cam 47 be 60 swung clear of, and away from the pawl 46, and for this purpose the cam is adapted to be rotated to the position indicated by 65 dotted lines in Fig. 5, in which position the

lateral extension 56, formed on the cam, rests in the pocket 51 heretofore referred to. The recessed portion formed in the flange 50 by the pocket 51 also affords great convenience to the operator in fingering the 70 cam 47, prevents jamming of the fingers and assures expeditious operation of the cars. The disposition of the wall 38 between the ratchet wheel 33 and the plate 27 necessitates the spacing of the ratchet wheel somewhat 75 away from the plate and in order to maintain the locking pawl 46 and cam 47 in alignment with the ratchet wheel, bosses 57 and 58 are provided on the respective pawl and cam which effectively serve to maintain 80 the parts in the desired correct relationship.

It will thus be seen that this arrangement of locking and rotating mechanism where a single ratchet wheel is utilized both for locking and operating enables the same to 85 be disposed in a very small space and does away with the necessity of placing the ladder unduly far from the end of the car while at the same time assuring that the parts do not project beyond the end of the 90 car.

Although I have herein shown and described my invention as embodied in the preferred form, the same is merely illustrative and I contemplate all changes and modifications that come within the scope of the 95 claims appended hereto.

What I claim is:

1. In a dump car door operating and locking mechanism, the combination with a car side wall; of a plate extending outwardly from the car; an operating shaft passing through the said plate; a ratchet wheel on the shaft adjacent said plate; a bracket disposed above the shaft, spaced from said plate, 100 and secured to the car side wall and projecting outwardly therefrom; locking means disposed between said bracket and plate and pivotally connected thereto, said means including a locking pawl adapted for engagement with the ratchet wheel and a locking cam adapted to lock the pawl relatively to the wheel, said pawl and cam having interlocking portions whereby the pawl may be 105 maintained out of its engagement with the ratchet wheel; and means associated with said bracket whereby the pawl may be maintained out of its engagement with the locking pawl.

2. In a dump car door operating mechanism, the combination with a ratchet wheel; of a transverse car wall; a longitudinal shaft rotatably mounted in said transverse wall; a ratchet wheel rotatable in unison with the shaft; a pawl pivotally mounted on the transverse wall and adapted to lock the ratchet against rotation; a cam pivotally mounted on the transverse wall and adapted to lock the pawl with respect to the ratchet wheel; co-operating means between said cam 120

125

130

and pawl whereby the pawl may be held in released position with respect to the ratchet wheel; a bracket having a portion overlying the cam and pawl, said bracket having also 5 a portion secured to a side wall of the car; and a projection on the cam in alignment with the said overlying portion of the bracket whereby the said cam may be supported in overbalanced inoperative position.

3. In a dump car door operating mechanism, the combination with a side wall having an inwardly bent lower portion; of a transverse bracket plate extending outwardly from said side wall; a door operating shaft 15 extending through said transverse bracket plate; a ratchet wheel on the shaft adjacent the said plate; an angular shaped bracket secured by one of its flanges to the sloping side wall and having the other of its flanges 20 extending outwardly from the car; a locking pawl and a locking cam disposed between said bracket plates and pivotally mounted therebetween said locking cam having a lateral extension adapted to be engaged by the 25 vertical flange of the last named bracket whereby said cam may be maintained in an inoperative position with respect to the locking pawl.

4. In a dump car, the combination with a side wall having an inwardly bent portion, of an operating shaft extending longitudinally beneath the same; a transversely extending plate through which the shaft passes; a ratchet wheel fixedly mounted on 35 the shaft, said ratchet wheel having hub portions on opposite sides thereof, one of said hubs being extended longitudinally through the plate and secured to the shaft on the side of the plate opposite to the ratchet 40 wheel; shaft rotating means rotatably mounted with respect to the ratchet wheel, said means including walls respectively disposed on opposite sides of the ratchet; a pawl pivotally mounted between said walls 45 and adapted to have clutch engagement with the ratchet wheel; a socket portion disposed on the outer of said walls, said socket portion being intermediate the end of the shaft and a plane defining the end of the car; and

shaft locking means including; a pawl and 50 cam, said pawl being adapted to engage the upper face of the ratchet, and said pawl and cam being pivotally mounted between the said transverse plate and a bracket carried by the inwardly deflected portion of the 55 car side.

5. In a dump car door operating mechanism, the combination with a shaft having a ratchet member affixed thereto; of an actuating device pivotally supported by said 60 shaft, and having portions offset with respect to said shaft; an operating pawl pivotally carried by one of said offset portions; means on said actuating device disposed co-axially therewith, for the reception of an operating 65 element; a locking pawl overlying said ratchet member and co-operating therewith; a support; and an element pivotally mounted on said support and in depending position 70 co-operating with said locking pawl to control the position thereof, said element being swingable out of engagement with said locking pawl to an overbalanced position with reference to said support so as to be held 75 in inoperative position thereby.

6. In a dump car, the combination with a side wall having an inwardly bent portion, of an operating shaft extending longitudinally beneath the same; a ratchet wheel fixedly mounted upon said shaft; a bracket 80 affixed to the inwardly bent portion of the car side, said bracket having a portion extending outwardly from the car side and overhanging said ratchet wheel; a locking pawl pivotally mounted on said bracket and 85 cooperable with the ratchet member to prevent rotation thereon; and an element pivotally mounted on said bracket and in depending position cooperable with said locking pawl to control the position thereof, said 90 element being swingable out of engagement with said locking pawl to an overbalanced position with reference to the bracket so as to be held in inoperative position thereby.

In witness that I claim the foregoing I 95 have hereunto subscribed my name this 5th day of February, 1925.

ARGYLE CAMPBELL.
